UNITED STATES PATENT OFFICE.

PHILIP S. OSGOOD, OF CLEVELAND, OHIO.

LIGHT PROJECTOR.

Application filed May 25, 1921. Serial No. 472,433.

To all whom it may concern:

Be it known that I, PHILIP S. Osgood, a citizen of the United States, and resident of Cleveland, in the county of Cuyahoga and State of Ohio, have invented certain new and useful Improvements in Light Projectors, of which I hereby declare the following to be a full, clear, and exact description, such as will enable others skilled in the art to which it appertains to make and use the same.

The invention relates to lamps such as are employed in the use of vehicles at night, the purpose being to project a beam of light upon a confined area at a distance.

It consists of a combination of certain means employed heretofore, with certain new and essential features, to provide a lamp of new achievement, that is for the conversion of all the light possible from a given source into a beam of controlled dimension and shape, with a minimum amount of diffusion and loss of rays.

In principle and in application this invention is an improvement over existing lamps of similar purpose in the following respects:

First: It accomplishes its purpose without causing reflected rays to pass from a parabolic surface through a lens, which is fundamentally wasteful on account of the loss in cross rays.

Second: There are no free rays, all of the rays are directed into the controlled beam.

Third: It eliminates the use of plane or tubular surfaces placed in the path of the beam to prevent lateral escape of light, which surfaces can function only at the expense of rays absorbed and also prevent the expansion of the beam. This feature is of vital importance.

Fourth: The control of the shape of the beam and therefore of the field of illumination by the use of a lens which is ground to function as desired. This feature is also of great importance. The lens is made to project as much as possible of the total light produced. The remaining rays are projected by a parabolic reflector, not through the lens, but into the beam projected by the lens.

Fifth: The use of a reflector of semi-spherical shape to focus back through the source as much of the light as the lens can encompass. Throwing these light waves back to the source has the effect of increasing the temperature and therefore the efficiency of

the filament in the case that the usual electric lamp is employed. The fact that they are reflected in an inverted image also increases the dimension of the source, and all waves radiate virtually from this one point. Increasing the temperature of the filament is also desirable particularly because the energy of a storage battery such as vehicles make use of is progressively lowered with age.

Sixth: That given a source of equal light energy it will produce a more intense field of illumination, size for size, than any other type of lamp, for the simple reason that it brings into that field every available ray. And that all the foregoing objects are accomplished, by the inexpensive and rugged assembly of easily fabricated parts.

The invention is hereinafter more fully described, illustrated in the accompanying drawings, and specifically pointed out in the claim.

In the accompanying drawings, Fig. 1 is a longitudinal horizontal section of the lamp; Fig. 2, is a front elevation thereof; Fig. 3 is a diagram illustrating the return of the reflected rays to the source of light; Fig. 4, is a diagram illustrating the inversion of the reflected image at the source; Fig. 5, illustrates the effect of the improved lamp, which projects a beam which is elongated transversely in cross section, and forms a field of illumination which is nearly circular in form and covers two wheel tracks or a field as large as would be covered by the use of two spot lights. Fig. 6 is an elevation of the vertical edge of the preferable form of lens employed, and Fig. 7 is a plan of the edge of the lens looking from above the same.

The foregoing advantages are attained by the use of a reflector of part spherical and part parabolic surface, and by an astigmatic lens which is derived from a plano-convex lens by altering the plane surface of the lens to a horizontal cylindrical preferably concave surface, thus giving the lens at once different converging powers in the vertical and horizontal directions.

In the accompanying Fig. 1, the essential parts embodying the above mentioned improvements are exemplified.

Here the light is produced in the filament 1 of the incandescent electric lamp 2, of appropriate voltage and current characteristics. A cone of the light falls upon the

astigmatic lens 3, held in place by a suitable support and ring 4, and is projected after being made less divergent by the lens, its sides being almost parallel. The lens, as mentioned above, projects an elliptical beam which illuminates a nearly circular field in contrast to the usual elongated elliptical field. The value of this elliptical beam is obvious in the drawing of the roadway illumination, as shown in Fig. 5, and will be hereinafter discussed further.

In the rear, and opposite the cone of light just described, almost a whole hemisphere of light falls upon the substantially semi-spherical portion, 5^a of the reflector, which is as nearly concentric with the source of light as possible; and is designed to reflect the light back again to the source, that is, to the filament, and the light continues past the filament to unite with the cone, falling directly upon the lens, or, when it passes outside of the lens, it falls upon the parabolic portion, 5^b, of the reflector, and when it encounters the filament, tends to slightly raise its temperature. The remainder of the light, from the source, 1, falls directly upon the parabolic portion, 5^b, of the reflector, and is projected therefrom in a nearly parallel beam in the usual manner. It will be seen that all the light is refracted or reflected to the field intended to be illuminated by the lens, except such small amounts as fall upon the base, 2^a, of the lamp, 2, or the relatively small areas of the lens support, 4.

The lamp is held in the customary Edison socket, 2^a, of single or double contact, adapted to this construction, which is not different from ordinary practice. The reflector is surrounded and protected by a suitable case, 6, which may also serve to give the external appearance to the lamp. The plain glass, 7, is employed merely to protect the reflector and lens from dust, moisture, tarnish, etc., and is held in position by any suitable arrangement, as shown at 8. The silvered and polished reflector, 5^a and 5^b, is adapted to give a broad or narrow focus by some simple adjustment, as shown at 9. The reflector is made movable longitudinally of the exterior casing towards and away from the source of light, and is adjusted by means of the spring and set screw, 9, or other simple means, the supports being firmly attached to the shell, 6, passing through the slits, 6^a, in

the reflector, sufficiently long to permit of appropriate movement of the reflector. The return of the reflected rays from the semi-spherical portion of the reflector, 5^a, to the source is shown in diagrams RR of Fig. 3, 60 and with the inversion of image, (R) Fig. 4.

In Fig. 5 is shown diagrammatically the illuminated field of the elliptical beam. The enormous elongation of the illuminated area along the direction of the circular beam is 65 well known in previous use by the shape of the intersection of that beam on a plane surface such as the road in front of a vehicle, and the diagram is self-explanatory. The value of the increased size and concentrated 70 scope of the elliptical beam reveals itself in Fig. 5, without argument. The intersection of the elliptical beam, 3^a, in Fig. 5, from the improved lamp of this invention, 75 forms a nearly circular field of illumination, 4^a, and covers efficiently both wheel tracks (a) and (b), doing away with the necessity of using two spotlamps to accomplish the same end.

In further explanation of the action of 80 the lens it might be said that the lens in front at Y functions precisely as a convex lens to project a slightly spreading or diverging beam, with a sufficient amount of flattening caused by a cylindrical concave 85 surface X on the rear face of the lens to flatten horizontally the beam so that it will not be elongated in the direction of the roadway or in the direction of the axis of the beam. 90

Having described the invention, what I claim as new, and desire to secure by Letters Patent, is:

In a lamp for the purpose set forth, an outer casing, a reflector, provided with a 95 semi-spherical portion and a parabolic portion, a source of light and an astigmatic lens spaced therefrom, said source of light and lens being rigidly secured to said casing within said reflector, said source of light 100 being at the focal point of said semi-spherical portion of said reflector, said reflector being longitudinally adjustable in said casing relative to the source of light.

In testimony whereof I hereunto set my 105 hand this 17th day of May, 1921.

PHILIP S. OSGOOD.

In presence of:

S. A. WILLIAMSON,
Wm. M. MONROE.
